UNITED STATES PATENT OFFICE.

REUBEN STANLEY SMITH, OF MILWAUKEE, WISCONSIN, ASSIGNOR TO A. O. SMITH CORPORATION, OF MILWAUKEE, WISCONSIN, A CORPORATION OF NEW YORK.

DIE FOR DRAWING PRESSES.

Application filed February 20, 1922. Serial No. 537,914.

To all whom it may concern:

Be it known that I, REUBEN STANLEY SMITH, a citizen of the United States, and a resident of the city of Milwaukee, county of Milwaukee, and State of Wisconsin, have invented a certain new and useful Improvement in Dies for Drawing Presses; and I do declare the following to be a clear, exact, and complete description of the invention, 10 such as will enable persons skilled in the art to which it relates to make and use the same, reference being had to the accompanying drawing for an exposition of the details of some constructional forms in which I 15 have chosen to embody my said invention.

The invention relates to the dies used in a press for drawing sheet metal blanks into shaped articles, such, for instance, as the channels which constitute the flanged side 20 bars and cross bars of an automobile or other vehicle frame.

The die members constituting the matrix of the presses heretofore employed for this purpose have been formed in short sections, 25 the right angled abutting ends of which meet in planes which are perpendicular to the plane of the matrix. In a press used for drawing long blanks into shaped articles, such as the side bars of an automobile 30 frame, die sections in a considerable number have been required, the number thereof being determined by the length of the article to be drawn. It has been observed, with the use of die sections so formed and arranged, 35 that transverse lines or marks are produced upon the flanges of the drawn articles at the points where the die sections abut each other, due to the condition that that portion of the margin of the blank which forms 40 the flange moves in a fixed path over or parallel to the joint of the abutting die sections, during the drawing operation. This development upon the exterior surface of the flange of the channeled side bar or other 45 article constitutes a defect in the structure, in that the existence of the lines or marks so formed in planes transverse to the length of the bar creates conditions which induce crystallization of the metal thereat, with the 50 result that the structure is weakened at such points.

It is the purpose of my present invention to overcome the objection above noted. I achieve this result by forming the ends of 55 the die sections on lines or at angles which

depart from the perpendicular, so that such abutting ends are made to overlap or otherwise meet each other, and the joints between the die sections are removed from parallelism with the plane of movement of the 60 material to be drawn, when the latter is forced into the matrix by the pressure applied to the co-operating punch.

As a result of this varied angular or other arrangement of the joints between the abutting ends of the die sections forming the matrix, the material in being drawn wipes over the diagonal or irregular lines at the joints of the die sections, and an entirely 65 smooth exterior surface without the lines or marks referred to is produced on the flanges of the drawn article. Thus the causes which heretofore have tended to the fracture of the metal following crystallization in the areas affected are removed.

The novel features of my invention will be defined in the claims appended hereto.

In the drawings which accompany this specification:

Figure 1 is an isometric view of the matrix 80 of a drawing press, showing the arrangement of my improved system of dies.

Fig. 2 is a vertical section on the line 2—2, Fig. 1, longitudinally of the matrix, and showing how the die sections overlap each 85 other at their meeting ends.

Fig. 3 is a vertical sectional view transversely of the matrix, on the line 3—3, Fig. 1.

Fig. 4 is an isometric perspective of one 90 of the die members.

Fig. 5 shows a construction in which the ends of the die sections overlap in reversed or contrary directions.

Fig. 6 shows a modified formation of the 95 abutting ends of the die sections, whereby the latter are engaged along irregular lines.

Figs. 7 and 8 are views in elevation and plan, respectively, illustrating the formation 100 of the faces of the dies with minute diagonal grooves, for a purpose to be described.

In the drawing, the numeral 10 indicates the usual shoe of a drawing press in which the die sections or members 11 constituting a matrix are placed. These die members 105 or sections will be assembled with their opposing faces 12 suitably formed and arranged to effect the production of the drawn flanges of an article of desired contour.

Instead of forming the die section or mem- 110

bers 11 with their abutting ends standing in vertical planes, as heretofore, I may incline or bevel the ends as at 13, so that such ends will overlap in the manner illustrated in Fig. 2, when assembled in the shoe. The inclined joints so provided will present what is practically an unbroken vertical surface upon the acting faces 12 of the die sections, over which joints the margins of 10 the blank which are to form the flanges will wipe with a relatively diagonal motion. This action will eliminate the formation of the marks which have heretofore been incident to the use of the dies in which the 15 joints between the sections stand in planes parallel to the path of movement of the material being drawn, and so wholly perfect work will be produced.

The degree of inclination from the perpendicular of the beveled faces 13 on the abutting ends of the die sections 11, should be uniform in all of the sections constituting a set, in order that a compact arrangement of the die sections may be secured, and no 25 openings left between such abutting ends, when assembled in the shoe. However, such degree of inclination may be varied in different sets of die sections, but it should be such in all sets that no space will be left for 30 the lateral extrusion of the metal of the blank under the pressure applied to the punch to force the blank into the matrix of the press. The die sections 11 will be substantially rectangular in cross-section.

35 In Fig. 5, I have shown a construction in which the ends of the die sections are beveled in reverse directions, this arrangement tending to an equalization and distribution of the pressures when the punch enters the matrix.

40 Fig. 6 shows the abutting ends of the die sections as formed on irregular vertical lines, as at 14, which may be varied into other forms than that shown, with like results.

45 In Figs. 7 and 8, I have shown the vertical face of the die sections, the ends of which may be formed at any desired angularity, as provided with minute grooves or scores 15, extending diagonally to the longitudinal 50 plane of the dies, the purpose of this construction being to exert a smoothing action upon the outer surface of the flanges of the bar, as the metal blank is forced into the matrix of the press. It is preferable that 55 the grooves or scores be arranged in such proximity that the area of the blank trav-

ersed by one groove will approach or overlap that of the contiguous groove, in order that the whole surface of the flange may be subjected to the smoothing pressure.

60 Having thus described my invention, what I claim and desire to secure by Letters Patent of the United States, is:—

1. Dies constituting the matrix of a sheet metal drawing press, the said dies being 65 formed in sections with ends which overlap, to eliminate die marks on the exterior of the drawn article.

2. Sectional dies for the matrix of a sheet metal drawing press, the said dies having 70 their abutting ends formed in planes which depart from the perpendicular of the longitudinal plane of the dies, to eliminate die marks on the drawn article.

3. In a sheet metal drawing press, a shoe, 75 and dies therein constituting the matrix, the said dies being formed in sections with their abutting ends angularly arranged to eliminate die marks on the exterior of the drawn article.

4. As an article of manufacture, a die section for a metal drawing press, substantially rectangular in cross-section and having its ends beveled or inclined with relation to the longitudinal plane of the die 85 section.

5. In a sheet metal drawing press, dies constituting the matrix thereof, the said dies being formed of sections the ends of 90 which abut in planes departing from the perpendicular and with grooves on their faces to exert a smoothing action upon the face of the flanges of the article being drawn.

6. In a sheet metal drawing press, dies having their faces formed with diagonal 95 grooves or scores to exert a smoothing pressure upon the face of the article being drawn.

7. As an article of manufacture, a die having its ends formed in planes which depart from the perpendicular of the longitudinal plane of the die and with grooves or 100 scores upon its face to exert a smoothing action upon the surface of the material being drawn.

105 In testimony whereof, I have signed my name at Milwaukee, this 3d day of February, 1922.

R. STANLEY SMITH.
